CLAIM

The ornamental design for a display screen or portion thereof with a graphical user interface for a surgical instrument, as shown and described.

DESCRIPTION

FIG. 1 is a front view of a first embodiment of a display screen or portion thereof with a graphical user interface for a surgical instrument; and,

FIG. 2 is a front view of a second embodiment thereof. The outermost evenly spaced broken lines illustrate the display screen or portion thereof and form no part of the claimed design. The other evenly spaced broken lines illustrate portions of the graphical user interface and form no part of the claimed design. The dot-dot-dash broken lines represent the boundaries of the claimed design and form no part thereof.
